UNITED STATES PATENT OFFICE.

HEINRICH THEODOR PESTALOZZI, OF ZURICH, SWITZERLAND.

DEVICE FOR CROSS-WEAVING.

No. 852,520.

Specification of Letters Patent.

Patented May 7, 1907.

Application filed August 23, 1905. Serial No. 275,460.

To all whom it may concern:

Be it known that I, HEINRICH THEODOR PESTALOZZI, a citizen of Switzerland, residing at Zurich, in the Canton Zurich, Switzerland, have invented a new and useful Device 5 for Cross-Weaving, of which the following is a specification.

In gauze weaving the weaver has to work with pairs of warp threads, one of each pair being termed the "ground-warp" and the other the "crossing-warp" or "whip-warp," so that on the one treadle movement or on one pick the whip warp thread will be brought up on the right side of the ground warp, and that on the next pick the whip warp thread will be brought up on the left side of the ground warp. This has heretofore been accomplished by the employment of a back harness together with a front harness, or in 15 jacquard gauze weaving by the employment of mails serving as a back harness together with mails serving as a front harness.

The back harness has heretofore been made after the manner of a taffeta harness, 25 while the front harness was the gauze harness proper, being composed of guide healds or standards and of gauze-half-healds or doups. Each ground warp and each whip warp was drawn once through a gauze-half-heald. The number of gauze-half-healds 30 was thus equal to the number of ground warp threads plus the number of whip warp threads.

The distinctive feature of the gauze-half-heald proper is, that on the one treadle movement the gauze-half-heald proper is set in motion by the warp thread (which for its part heretofore was moved by the back harness) and that on the other treadle movement the warp thread is set in motion by the gauze-half-heald proper. In other words, in the case where the warp thread is moved by another agency than by the gauze-half-heald proper itself (see Figure 2 and consider the 35 work of any gauze-half-heald proper, for instance the work of the gauze-half-heald proper o^2) the gauze-half-heald proper follows the warp thread without resistance into the position given to said warp thread by 40 said other agency (in Fig. 2 the warp thread S has been moved, viz. lowered, by o^1 , while the gauze-half-heald proper o^2 , which interests us, has followed it without resistance), while in the other case, (see Fig. 3 and consider again this same gauze-half-heald proper 45 o^2) the gauze-half-heald proper itself gives

the position to the warp thread (in Fig. 3 it was this very gauze half heald o^2 that brought the warp thread S in its position).

In the employment of back harness and 50 front harness the gauze-half-healds perform active work only on the one treadle movement, namely on the so called gauze-treadle movement, drawing apart the warp threads to form a shed: while on the other treadle 55 movement, on the so-called taffeta-treadle movement, the active work of shedding the warp threads is effected by the back harness, and all the gauze-half-healds proper only passively follow the warp threads. 70

In the employment of back harness and front harness there is the disadvantage that the harness as a whole, that is, both the back harness and the front-harness together, occupies a large space measured from the front toward the back, and is therefore inconvenient for many operations. Also in the employment of back harness and front harness, on the movement of the front harness, tension is produced between the back harness and the 75 front harness. The consequences of this tension are increased strain on the warp threads, and increased wear of the harness, and therefore reduced output and increased expenses.

Many attempts have been made to overcome the said draw-backs. For instance gauze-healds with double guidance have been proposed. In such healds, instead of the gauze-half-healds proper a form of gauze-half-healds, has been used, of which it is explicitly stated that on no treadle movement is it operated by the warp, but that on the one treadle movement it is operated by a left-hand guide-heald, and on the other treadle-movement it is operated by a right-hand 90 guide heald. 95

In the case of gauze healds with double guidance, the back harness may be dispensed with, but with finer webs the gauze healds with double guidance cannot be used. 100

The improved apparatus forming the subject of my present invention likewise renders it possible to dispense with the back harness, and so avoid the drawbacks indicated, while still enabling the finest fabrics to be woven. 105

Fig. 1 of the annexed drawing shows a portion of an apparatus forming one embodiment of my invention in elevation in the position of rest: Figs. 2 and 3 are elevations showing the apparatus at the end of the two 110 treadle-movements.

As shown, S indicates the ground warp

thread: D the whip warp thread: F^1 , F^1 and F^2 , F^2 the guide healds corresponding to the same pair of warp threads: o^1 and o^2 , and u^1 and u^2 indicate the gauze-half-healds proper corresponding to the said guide healds. The guide-healds are on shafts which have an invisible movement due to the treadles. Each ground warp thread and each whip warp thread is drawn through two gauze-half-healds proper o^1 , o^2 or u^1 , u^2 . The number of gauze-half-healds proper is thus twice: the number of ground warp threads plus the number of whip-warp threads.

In operation, when the guide heald F^1 , F^1 is moved downward, the guide heald F^2 , F^2 rises, and vice versa. When F^1 , F^1 is lowered, the gauze-half-heald proper o^1 is drawn downward therewith, and the ground warp thread S comes, as the gauze-half-heald proper o^2 follows S without resistance, downward to the left of the whip warp thread D (Fig. 2). The guide heald F^2 , F^2 rising, the gauze-half-heald proper u^2 is raised therewith, and the whip warp thread D comes, as the gauze-half-heald proper u^1 follows it without resistance, to a point upward to the right of the ground warp thread S. If on the other hand the guide heald F^2 , F^2 be lowered (see Fig. 3) the gauze-half-heald proper o^2 is drawn downward therewith, and the ground warp thread S comes, as the gauze-half-heald proper o^1 follows it without resistance, downward to the right of the whip warp thread D. The guide heald F^1 , F^1 rising, the gauze-half-heald proper u^1 is raised therewith, and the whip warp thread D comes, as the gauze-half-heald proper u^2 follows it without resistance, to a point upward to the left of the ground

warp thread S. From this arrangement, wherein both on the treadle movement heretofore called the movement of the gauze treadle, and on the treadle movement heretofore called the movement of the taffeta treadle, the shed is formed exclusively by means of gauze-half-healds proper, under otherwise like conditions there are effected reduction in expenses and increase of production. It is evident that the new arrangement may be used in Jacquard looms as well as in shedding motions. The manner of mounting the gauze-half-healds will be understood from Figs. 1, 2 and 3 without further description.

What I do claim as my invention, and desire to secure by Letters Patent is:—

In a device for operating the warp threads in gauze weaving, the combination of two gauze-half-healds o^1 , o^2 for the whip warp thread and of two gauze-half-healds u^1 , u^2 for the ground warp threads, with two guide healds F^1 , F^1 , F^2 , F^2 , in such manner that the gauze-half-heald o^1 embraces the ground warp thread S and the guide heald F^1 , and the gauze-half-heald u^1 embraces the whip warp thread D and the guide heald F^1 , and that the gauze-half-heald o^2 embraces the ground warp thread S and the guide heald F^2 , and the gauze-half-heald u^2 embraces the whip warp thread D and the gauze-half-heald F^2 .

In witness whereof I have hereunto signed my name this seventh day of July 1905, in the presence of two subscribing witnesses.

HEINRICH THEODOR PESTALOZZI.
